UNITED STATES PATENT OFFICE.

FRANZ A. BOEDTCHER, OF BERGENFIELD, NEW JERSEY.

ELEVATOR SIGNALING SYSTEM.

Application filed November 29, 1921. Serial No. 518,572.

This invention is an elevator signaling system and relates, more particularly, to elevator installations wherein passengers' push buttons, positioned at the several floors of a building, are adapted to be operated by intended passengers for the purpose of actuating signals in an elevator car, so that the car operator during the travel of the car up and down the shaft may know, when he is approaching a floor, whether or not passengers are waiting at such floor.

Various means for accomplishing this end are well known to the art, but, so far as I am aware, all of them rely for their operation upon a direct mechanical connection between a relatively stationary element and a relatively movable element operable by a moving car or some moving part of the "over-head" thereof. That is to say, the means for controlling the signal has invariably either direct wiring connection with the signal or is adapted to be operatively connected thereto by mechanically cooperating fixed and relatively movable elements. In many instances, the mechanical cooperation referred to comprises in the wiping of a brush over fixed contacts although, in other cases, dashpots and other forms of electrical switches are employed.

Mechanical connections between a moving car or moving parts of the overhead and relatively stationary parts, are, in practice, subject to considerable wear, which not infrequently results in breakage. Moreover, with such mechanical connections, slippage invariably occurs particularly when the mechanism is operated from the overhead, and this slippage results in false signals. In other words, the signals do not properly correlate with the movements of the car, so that a system wherein slippage has resulted will be apt to give signals either before or after the time when they should properly occur.

With these considerations in mind, the prime object of the present invention is to provide a simple, efficient and highly reliable means for electrically controlling the giving of signals in such manner as to entirely obviate the necessity of mechanical connections between the signal giving means in the car and the means for controlling the signal giving means positioned exteriorly of the car and free from movement therewith.

A further object of the invention is the

pronounced simplification of wiring in the signal system. In prior systems, the wiring for a plurality of floors, say for example the wiring of a ten story building, is such that it invariably extends throughout practically all of the floors. That is to say the wiring for the tenth floor forms a part of the wiring for the first floor and all intermediate floors, so that in installing such wiring, long lengths of wire or cable must be installed throughout the entire length of the shaft and the wiring for one floor may at times extend throughout the entire length of the shaft. This frequently requires a number of parallel leads which extend through several floors with each lead being adapted to carry out the signaling functions and only one of them. Manifestly, this method of wiring is wasteful and expensive and requires considerable loss of time in its installation.

In contradistinction to this prior method of wiring, the present invention provides for a simple form of wiring between a relatively small number of floors. That is to say, wiring may be duplicated for say every two floors. In other words, the wiring for the second and third floor may be substantially self contained and have practically nothing to do with the wiring of the fifth and sixth or first and second floors.

In practice, it is convenient and economical, under the present invention, to overlap the wiring of each two successive floors, although three floors may be overlapped if it is desired to give a signal of the delayed type when a car is approaching the second or third floor ahead of the one from which it has been signaled to stop.

It will be apparent that by this method of wiring, the duplication of long lines is entirely avoided and a very simple form of wiring diagram results, which wiring diagram may be constant for buildings of widely different heights. For example, a wiring diagram for a five story building may be substantially the same as the wiring diagram for a twenty story building, the diagram being simply duplicated from floor to floor or from series of floors to series of floors with mains or leads common to all the floors extending throughout the length of the shaft, so that the various units of the system may be fed through common leads from a source of electric supply. Of these mains or trunk lines, I may use some of them as a main to a

110

plurality of cars and also for both up and down directions and, in this way, I greatly minimize the wiring and render the installation unusually simple and economical to install and highly efficient in practice. In fact, experience has shown that there is practically no upkeep on account of the simple wiring and no mechanical connections as hereinbefore set forth.

10 By installing the several floors of a building through the employment of what may be termed electrical or wiring units, the installation in a building may proceed floor by floor or two or three floors at a time, during the 15 progress of putting up the building, so that by the time the last floor is completed, the electrical wiring is also substantially completed.

Considering the invention in one of its 20 important phases, and in the practical carrying out thereof, I mount in stationary position, vertically of the shaft, a plurality of electrical devices or instruments, which, through their operation, are adapted to effect 25 the giving of a signal in the elevator car. These electrical devices are adapted to be controlled by an electrical device or instrument mounted on and movable with the car, but without any mechanical connection between the electrical device on the car and the 30 electric devices in the shaft.

As the car travels in the shaft, the electrical device thereon is adapted to actuate the relatively stationary electrical devices in the 35 shaft which are so associated with the passenger's push buttons at the various floors that when the electrical devices in the shaft are operated by the electrical device on the car, a signal will be given in the car, as the 40 car approaches the floor at which a particular button has been operated, and comes within a predetermined signaling zone or distance.

In one of its practical forms, the electrical device or instrument on the car embodies an 45 electromagnet while the relatively stationary electrical devices or instruments of the shaft embody movable armatures, positioned substantially within the path of the electromagnet of the car, so that, as the car traverses the 50 shaft, the electromagnet thereof is successively brought into cooperative relation with the armatures of the stationary electric instruments of the shaft and operates said instruments in succession, through movement 55 of their armatures, due to the magnetic pull of the magnet of the car. This is the preferred construction, but I am aware that equivalent means may be employed without departing from this invention, such for example as electro, inductive means in place of the electromagnet and its armature referred to.

It will be apparent that in the construction specified, the magnet of the car does not 65 necessarily touch its armatures in the shaft

and consequently there is no mechanical connection whatsoever between the signal on the car and the instrument which operates it.

Another feature of the invention resides in the fact that in an installation embodying this invention, practically all of the circuits are normally dead and no maintaining circuits are required. This is highly important from a practical standpoint since it economizes in current consumption, and, furthermore, enables relatively light wiring and light magnets.

In practically carrying out the invention, the completion of the signaling circuit is of short duration; when delayed signals are so employed, the circuits for resetting the push buttons are only momentarily closed; and, the circuit for restoring the armatures of the shaft instruments into normal operative condition are also momentarily closed. Moreover, the system is such that the passenger's floor buttons may be used to signal one or more cars at the same time.

Features of the invention, other than those specified, will be apparent from the following description and claims, when read in conjunction with the accompanying drawings.

The accompanying drawings illustrate one practical embodiment of the invention, but the construction therein shown is to be understood as illustrative, only, and not as defining the limits of the invention.

Figure 1 shows diagrammatically the wiring diagram for one floor of a building, and

Figures 2 and 3 show elements of the diagram of Figure 1 in different operative conditions than those in which they are shown in Figure 1.

This invention is adapted for use in buildings having any number of floors and since its installation for several floors involves, practically speaking, mere duplication of the system for any particular floor, I have, in the interest of brevity and clarity of description, shown in the drawings, the system as associated with one floor and adapted for signaling a car when moving down the shaft.

In practice, the "down" signaling system shown in the drawings is duplicated for the up directional movement of the car and each of these systems is responsive to its particular passenger's push button of the corresponding floor.

Referring to the drawings, 1 designates an elevator car of any conventional type mounted for up and down movement in a shaft and propelled and controlled in any suitable manner. The present invention contemplates the use of signals of either the immediate or delayed type or both. Thus a lamp 2 is shown as exemplary for immediate signaling while a bell 3 and lamp 4

are exemplary of the delayed signal giving means. The signals are given through the operation of a passenger's push button 5 at a floor.

5 In carrying out the invention, I mount on the car an electrical device 6 movable with said car up and down the shaft and in fixed positions in the shaft are mounted certain electrical devices 7, 8 and 9, with which 10 the electrical device on the car is adapted to cooperate. While these electrical devices may differ in construction, their function and relation remain the same. That is to say, the electrical devices 7, 8 and 9 15 are adapted, when operated, to control certain electrical circuits and these devices are, in turn, controlled by and responsive to, the electrical device 6 of the car 1.

In a highly practical form of installation, 20 the device or instrument 6 is an electromagnet adapted to be energized from any suitable source of current supply and the current to this magnet is preferably so controlled that the magnet will be energized 25 when the car is descending and deenergized when the car is ascending. The device or instrument 7 embodies an electromagnet 10 with which cooperates an armature 11 pivoted at 12 and carrying a resilient switch arm 30 13 adapted, when the armature is attracted to engage with a fixed contact 14. The contact 14 and the switch arm 13 collectively constitute the "setting" switch of the system. Cooperating with the armature 11 is a bell 35 crank latch 15 pivoted at 16 and the foot of this latch carries a projecting pin 17. The shape of the latch normally causes it to gravitate into the position shown in Figure 1 wherein it lies out of the path of the armature and allows the latter to drop and disengage the switch arm 13 from contact 14. If, however, the latch is tilted 40 against gravity into the position of Figure 2, the latch bears against the armature and lifts it to bring the arm 13 into engagement with the contact 14. The armature 11 is provided on its under side with a shoulder or stop 18 back of which the nose of the latch is caught as shown in Figure 2. The latch is thereby held against gravitating 45 until the magnet 10 is energized to further lift the armature and release the latch so that the latter can fall back into the position of Figure 1.

50 Mounted on the pivot 16 which carries the latch is a swinging hanger 19 which constitutes the armature of the magnet 6 of the car, and this armature carries an arm 20 which projects into the path of the pin 17. The instrument 7 is operated automatically. When, through movement of the car, the magnet 6 is brought into juxtaposed position with its armature 19 of the instrument 7, the pull of the magnet 6 pivotally 55 moves armature 19 into the position of

Figure 2 and in so doing, the arm 20 engages the pin 17 and tilts the latch into the position of said figure, with the result that the switch arm 13 engages contact 14 and closes a circuit, hereinafter described, associated 70 therewith. This circuit remains closed at this point so long as the stop 18 locks the latch in place. That is to say, until the magnet 10 is energized, whereupon the parts return to their initial normal position of 75 Figure 1.

The device or instrument 8 is the same, in essential particulars, as the instrument 7. It embodies a magnet 21, armature 22, spring contact arm 23, contact 24, latch 25, pivoted 80 at 26 and an armature 29 for the magnet 6. Moreover these parts are operated in the same manner as the corresponding parts of Figure 1 by the magnet 6. The contact 24 and arm 23 collectively constitute the "re- 85 storing" switch of this system.

The device or instrument 9 embodies a switch 30 pivoted at 31 and adapted, when oscillated on the pivot 31, to momentarily contact with a spring contact 32. These 90 parts collectively constitute the "resetting" switch of the system. A spring 33 normally retracts the switch 30 into the full line position of Figure 1, but when the magnet 6 of the car is brought into juxtaposition with this switch, it attracts the switch, against the tension of the spring 33, from the full line position in Figure 1 to the dotted line position thereof. During this movement, the lower end of the switch wipes over the 95 spring contact 32 and completes a circuit associated therewith. As the car passes on and the magnet 6 moves out of juxtaposition with the switch 30, the spring 33 again acts to return the switch to the full line 100 position and again causes the lower end thereof to wipe over the contact 32 and again momentarily complete the circuit referred to.

The instruments or devices 7, 8 and 9 are 110 mounted in fixed position in the shaft in any suitable manner, but their positions are such that when the car travels up and down in the shaft, the magnet 6, is, through such travel, brought into relatively close proximity with the armatures 19, 29 and 30 of the instruments 7, 8 and 9 and operates them in the manner described. The instruments 7, 8 and 9 are included in electrical circuits, certain of which include an instrument 34 115 of which the push button 5 forms a part.

The instrument 34 is in many respects the same as the instruments 7 and 8. It embodies a magnet 35 having an armature 36, pivoted at 37 and carrying a resilient spring 120 contact 38 adapted when the armature 36 is lifted to be brought into engagement with a fixed contact 39, with which is associated one of the electric circuits of the system. A gravity latch 40 pivoted at 41 is adapted 125 130

to be operated upon directly by the push button 5 and forced against gravity into a position wherein it will elevate the armatures 36 and bring the spring contact arm 38 into engagement with the contact 39. In practice, the push button 5 may be normally spring retracted, but after the button is pushed the gravity latch is locked in position by a stop 42, associated with the armature 36 and corresponding to the stop 18 hereinbefore described. The instrument 34 has no part corresponding to the armature 19 of the instrument 7, as the instrument 34 is not acted upon by the magnet 6, but is operated manually through the push button 5.

The electrical circuits associated with the several instruments referred to and by means of which they are coordinated and cooperate for the fulfillment of their respective functions will now be described.

43 designates any suitable source of electric energy, which, for the purpose of illustration, is shown as a generator. The main 44 leads from the generator 43 and a branch 45 from this main leads to the gravity latch 40 of the push button instrument. From the contact 39, a wire 46 leads to the contact 14 and from the gravity latch 15 of the instrument 7 a wire 47 leads to the lamp 4. The lamp 4 and bell 3 are in series and from the bell wires 48, 49 and 50 lead back to the generator 43. The circuit described is shunted by a wire 51 which extends from the wire 46 to the wire 49 and includes the lamp 2. The wire 51 also includes a switch 52 and the wire 48 includes a switch 53. The switches 52 and 53 are manually operated, so that at the will of the car operator, he may receive either delayed or immediate signals. After the switch 52 is opened and the switch 53 closed, current flowing through the circuit described will illuminate the lamp 4 and ring the bell 3. On the other hand, if the switch 53 is opened and the switch 52 closed, the lamp 2 will be illuminated.

If the push button 5 is pressed, while the switch 52 is closed, and the armature 36 elevated, as shown in Figure 3, to close the circuit at the contact 39, current will immediately flow through the wires 44 and 45, gravity latch 40, armature 36, spring arm 38, contact 39, wire 46, wire 51, switch 52, lamp 2, wire 49 and wire 50 and by so doing will illuminate the lamp 2, thereby giving an immediate signal irrespective of the position of the car in the shaft.

If the switch 52 is opened and the switch 53 is closed, when the push button is pressed, the circuit will be closed at the instrument 34, but as soon as the circuit is broken at the contact 14, the circuit will remain dead until the car during its downward movement brings the magnet 6 into

cooperative relation with its armature 19 and closes the circuit at this point, whereupon the lamp 4 will be illuminated and the bell 3 will be caused to ring, thus giving a signal of the delayed type.

As the car continues down the shaft, the magnet 6 is next brought into cooperative relation with its armature 29 and in the manner hereinbefore described, operates upon its armature to bring the spring contact 23 into engagement with contact 24. This contact forms a part of the following circuit. A wire 54 leads from the main 44 through the coil of the magnet 35 of the push button instrument 34 and thence to the contact 24. From the gravity latch 25, wires 56 and 57 lead back to the generator, but in the wire 56 is included a switch 58, so operatively associated with the car or its operating mechanism that this switch will remain open unless the car stops at the floor on which the push button has been pressed. Switches of this character are generally known to the elevator signaling art as governor switches and are controlled either by the stopping of the car, the starting of the car or by movement of the car after starting. The switch structure forms no part of the present invention and any switch, the closing of which is dependent upon either the stopping of the car, the starting thereof or the opening or closing of the elevator shaft doors to take on a passenger will suffice for the carrying out of the present invention.

It will appear from what has been said that even though the magnet 6 of the car closes the circuit just described at the contact 24, this circuit will not be completed unless the switch 58 is closed. If it be assumed that the car stops at a floor, takes on the passenger who pressed the button 5, and proceeds on its way down the shaft it follows from what has been said that the switch 58 will be closed, at least momentarily, and such closing of the switch will complete the circuit described. As this circuit flows through the magnet 35 of the push button instrument, it will energize such magnet with the result that its armature 36 will be raised to release the gravity latch 40 and permit it to gravitate into the normal inactive position shown in Fig. 1. This resetting of the push button switch is thus, in the system shown, dependent upon the closing of switch 58, but I wish it understood that, in practice, the switch 58 may be entirely omitted without departing from this invention.

The circuit just described may be termed the push button resetting circuit as its function is to return the push button to initial position after it has been operated. The circuit hereinbefore described as including the contact 39 of the push button instrument,

the contact 14 of the instrument 7 and the delayed signals 3 and 4, may be aptly termed the delayed signal circuit. The shunt circuit 51 which includes the lamp 2 may be accurately described as the immediate signal circuit.

I have assumed in describing the push button resetting circuit that the car has stopped and taken on passengers from the floor at 10 which the push button 5 is positioned and so effected a resetting of the push button. As the car proceeds down the shaft and passes the instrument 9, the magnet 6 acts upon its armature 30 to momentarily complete a circuit at the contact 32. This circuit includes the following wiring. A wire 59 leads from the generator 43 to the magnet 10 of the instrument 7, thence to the magnet 21 of the instrument 8 and thence to the switch 30. 20 This wire 59 includes the magnets 10 and 21 in series with the switch 30. From the contact 32, a wire 60 leads to the wire 57, which connects with the generator. Accordingly, the operation of the switch 30 by the magnet 6 of the car causes a momentary impulse of current to pass through both magnets 10 and 21. Such impulse of current will simultaneously reset the instruments 7 and 8 and open the delayed signal circuit and the 30 push button resetting circuit at these instruments, thereby leaving the parts in their normal unset condition and ready to be again operated in the manner hereinbefore described through the pressing of the push button 5. The circuit just described as including magnets 10, 21 and switch 30, may be aptly termed the switch resetting circuit, since its function is to restore the instruments 7 and 8 to normal inactive condition.

40 It has been assumed up to this time that the car is stopped at the floor and taken on the passengers. In practice, when wiring a building having a plurality of elevator cars, I preferably connect the wiring of the various shafts, so that when a push button is operated on a particular floor, the signal giving mechanism of all cars will be responsive to that particular push button or a series of push buttons on that floor, so that if one car is full and cannot stop and take on additional passengers, it may proceed along its way, and past the floor without cancelling the signal, so that said signal may be picked up by the next car. This connecting of a 50 number of car signals is common in the elevator art and the manner in which the wiring system of the drawings may be adapted to an installation of a plurality of cars will be readily understood by those skilled in the art.

55 If it now be assumed that the car 1 has not stopped at the floor, but has proceeded down the shaft, the operation of the switch 30 of the instrument 9 will reset both the instruments 7 and 8 of the car 1, but will not

influence the corresponding instruments of other cars, which are responsive to the push button and will be operated when some other car comes within the signaling zone.

If desired, floor lamps may be used in conjunction with the system of this invention. That is to say, lamps may be positioned at the various floors of the building to be used to notify passengers of the approach of the car. Such a lamp is shown at 75 61 in Figure 1. It is connected with the source of current supply 43 through wire 50 and wire 62, while from the lamp 61, a wire 63 leads to the pivot 12 of the armature 11.

In practice, the instrument 7 is positioned above the floor where the push button 5 is located and at which the lamp 61 is positioned, so that as the car approaches the floor, the car magnet 6 passes the armature 19 of instrument 7 before said car reaches 85 the floor. In practice, the instrument 7 may be positioned one or two floors or even three floors above the floor at which the push button 5 is located, so that as the car moves down the shaft, in approaching the floor 90 where the push button is, the magnet 6 in passing its armature 19 sets the instrument 7 and completes the circuit through the lamp 61 by way of the wires 50, 62 and 63, through switch 13 and contact 14, wire 46, contact 39, 95 switch 38, armature 36, latch 40, and wires 45 and 44. In other words, the floor lamp circuit may be operated in conjunction with the car signaling circuit, so that at the same time the car operator gets the signal from the floor, the floor is signaled of the approach of the car.

From the foregoing detailed description of the simple wiring diagram shown in Figure 1 of the drawings, those skilled in the art 105 will readily appreciate the simplicity and practical merit of the present invention. In wiring a building having a number of floors, the wiring diagram is substantially duplicated for the various floors. This does not 110 mean that at each floor the wiring diagram shown in Figure 1 will be found, but each floor will have associated with it such a series of circuits. This series of circuits may extend up or down the shaft for one, two or even more floors, but in making the installation, the circuits of one floor will overlap the circuits of the next one or two floors. The purpose of this is that a car may receive a delayed signal at one or two floors above or below the floor on which it is to stop. If the instrument 7, for example, were placed at the third floor and was operated by a push button positioned on the third floor, it is 115 obvious that the car operator would not receive the signal from the push button until the car had arrived at the third floor and this would not give the operator time to stop the car before he passed the floor.

It is desirable in elevator installations to 120 125 130

signal two or three floors ahead and this explains the overlapping of the circuits of the several floors. Theoretically speaking, the system of the present invention might be 5 built up of separate and independent units positioned at each floor and not overlapping as described, so that the systems could be installed floor by floor as the building is being built. This statement is made in order 10 that the unitary character of the system of this invention may be appreciated and that it may be understood that the top and bottom floors of a twenty story building do not form part of the same wiring system of 15 either floor or for the intermediate floors.

Of utmost importance is the fact that the instrument 6 carried by the elevator car has no mechanical connection with the instruments 7, 8 and 9. Moreover, there is no 20 wiring between these instruments, the latter set of instruments are operated from the former instrument purely by magnetism. I am aware that the instruments 6, 7, 8 and 9 might be modified, so as to render the instruments 25 7, 8 and 9 operable by an induced current from the instrument 6. However, the magnetic control is preferred. In the use of either magnetism or an induced current, mechanical or wiring connections between 30 the operating parts of the instruments 7, 8 and 9 and the instrument 6 which actuates these parts is entirely obviated with consequent elimination of difficulties and disadvantages, well known as prevalent in prior 35 systems, where the signal giving means is controlled through mechanical connections with a car or with the "overhead".

In the system described, the signals are coordinated with the movement of the car at 40 all times and at the same time the cost of wiring and labor is reduced to a minimum.

Another important feature of the invention resides in the fact that all circuits are normally dead, except the circuit to the instrument 6. No current is needed to operate 45 the push button or maintain it in signal giving position. The pressing of a push button mechanically locks the button in signal giving position and it is mechanically held there until electrically released by a 50 circuit normally dead.

It will, of course, be understood that while I have shown only the circuits for the down signals of the car 1 that these are duplicated 55 for the up signals of such car. It has not been considered necessary to illustrate the wiring diagrams of two such coordinated signals, as anyone skilled in the art will readily understand the manner of installing 60 them.

Throughout the foregoing detailed description of the invention, in its preferred form, the instruments 7, 8 and 9 have been described as mounted in stationary positions

in the shaft, while the instrument 6 has been 65 described as mounted on or carried by the car. This is the preferred construction, but not the exclusive one. For example, the instruments 7, 8 and 9 may be mounted in the shaft in stationary positions while the instrument 6 may be associated with the counterbalancing weights of the elevator car. This latter construction will work out very 70 satisfactorily in practice, though, of course, slight stretching or contracting of the cables 75 would be apt to cause the signals to be given a little sooner or a little later than as they were originally adjusted. Moreover, if desired, the instruments 7, 8 and 9 may be mounted on the "overhead" and instrument 80 6 operated from the "overhead" in synchronism with the movements of the elevator car. Accordingly, the present invention is not restricted to the specific situations of the instruments 6, 7, 8 and 9 which placements 85 may be varied without changing their functions in substance or substantially changing their mode of operation.

From what has been said, it becomes apparent that one of the fundamental or generic features of the present invention resides in the novel principle of operation exemplified by the control of the instruments 7, 8 and 9 by the instrument 6 across the intervening space, whereby the use of wiring 90 connections or mechanical connections, such as trips, wipers or brushes are entirely dispensed with. The transmission of energy through space, and, specifically, the transmission of electrical energy through the 95 space intervening the controlling instrument and the instrument to be controlled, is, in the preferred manner of practicing this invention, electromagnetic, though, if desired, 100 electrical induction may be employed. This mode of operation and control of signals of 105 an elevator signaling system is broadly novel and its employment results in a marked advance in the art, and not only as producing high efficiency, but, also, in the minimizing 110 of installation and maintenance costs.

The practical performance of this invention is based upon a novel method forming part of this invention, as will be apparent from the foregoing description.

In installing the system of the present invention, it may be associated with cars of either the hydraulic, electric or purely mechanically operated types, and, in these different environments, it may be changed or modified, as by the substitution of equivalents, to best suit the particular environment in which it is installed. Accordingly, the invention is not restricted to the specific 120 showing hereinbefore advanced, and illustrated in the drawings, but is to be construed as broadly novel as is commensurate with the appended claims.

Having thus fully described the invention, what I claim as new and desire to secure by Letters Patent is:

1. In an elevator wiring system, the combination with an elevator cage mounted to travel vertically in an elevator shaft, of a normally inactive electric device carried by the cage, magnetically operated switch means positioned in the shaft, a circuit including 10 said electric device and magnetically operated switch means, and a magnet carried by the cage in a position to be moved with the cage past and in relatively close proximity with the magnetically operated switch means in the shaft for the purpose of closing said electric device circuit, said switch means including means for holding said device circuit closed after operation by said cage magnet, and means for restoring said switch means 15 to normal open position.

2. An elevator wiring system embodying an elevator cage mounted for vertical travel in an elevator shaft, and electric device carried by the cage, a magnetically operable 25 switch in the shaft, a circuit including said magnetically operable switch and electric device, a magnet carried by the cage in a position to be moved with the cage past and in relatively close proximity with the switch 30 in the shaft for operating said switch to energize the electric device, said switch including means for holding the switch closed after it has been closed by the magnet, and means for restoring the switch to normal 35 open condition.

3. An elevator wiring system embodying an elevator cage mounted for vertical movement in an elevator shaft, a magnet carried by the cage, a plurality of magnet controlled 40 switches corresponding to several floors of the building and mounted in fixed positions in the shaft, so that through movement of the cage, the magnet thereon is brought into relatively close proximity with said switches in succession, a normally inactive electric 45 device on the cage, electrical circuits including said electric device and also said switches, means for locking the switches closed after they have been closed by a magnet on the cage to selectively actuate said electric 50 device, and means for thereafter opening said switches to selectively render said device inactive.

4. An elevator wiring system embodying 55 an elevator cage, an electric device carried by the cage, magnetically operable means positioned partially on and partially off the cage for energizing the electric device, a magnet mounted on the cage and movable 60 therewith for magnetically operating the magnetically operable means when said magnet is in proximity to a portion of said magnetically operable means which is positioned off the cage, said magnetically operable 65 means being constructed to maintain the

electrical device in energized condition after it has been energized, and means for thereafter operating the magnetically operable means to de-energize the electrical device.

5. An elevator wiring system embodying 70 an elevator cage, an electric device carried by the cage, means for energizing and de-energizing the electric device embodying electric switches mounted off the cage in substantially fixed vertical alignment relative to the shaft, a magnet carried by the cage in a position to be carried by the cage into proximity with the switches in succession for operating said switches in succession for the purpose of energizing and de-energizing the 75 electric device when said magnet comes into proximity with said switches, and means for maintaining certain of said switches closed until another of them is operated.

6. An elevator wiring system embodying 80 an elevator cage mounted for vertical movement in an elevator shaft, an electric device carried in the cage, switch mechanism mounted in relatively fixed position in the shaft, wiring connections between the switch 85 mechanism and the electric device, means mounted on the cage and movable therewith past the switch mechanism for transmitting energy through the space between the switch mechanism and said means to operate the 90 former from the latter to operate the electric device when the former and the latter are substantially juxtaposed, said switch mechanism including means to lock the switch 95 closed after it has been closed, and means for 100 thereafter unlocking said switch to allow the opening thereof.

7. An elevator wiring system embodying 105 an elevator cage mounted for vertical movement in an elevator shaft, a signal on the cage, a switch in the shaft provided with an armature, when magnetically operated, to close said switch, electrical connections between said switch and the signal in the cage whereby the latter is controlled by the former, a magnet mounted on the cage and movable therewith past the switch armature and in proximity thereto, while free from contact therewith for the purpose of moving the armature to actuate the switch and set the 110 signal, means for maintaining the switch closed after it has been closed, and means for 115 thereafter opening the switch.

8. An elevator wiring system embodying 120 an elevator cage mounted to vertically travel in an elevator shaft, a signal carried by the cage, electromagnetic means for effecting the setting of said signal, which electromagnetic means is positioned partially in stationary position in the shaft, and another part of 125 which electromagnetic means is carried by the cage into and out of relatively close proximity with a part of the electromagnetic means mounted in the shaft and without mechanical or wiring connections therewith, an 130

electric circuit including the signal in the cage and the part of the electromagnetic means which is positioned in the shaft, means for maintaining the signal set after it 5 has been set, and means for thereafter canceling the signal.

9. An elevator wiring system embodying an elevator cage, an electric device carried by the cage, a magnet operated switch for controlling the electric device, a push button controlled switch adapted to be closed upon operation of the push button, a circuit including the electric device, the magnet operated switch and push button controlled switch, means for locking the push button controlled switch closed after it has been closed, and a magnet carried by the cage past and in relatively close proximity with the magnet operated switch for actuating the 10 magnet operated switch to complete the circuit to the electric device after the push button controlled switch has been closed, means for holding the magnet operated switch closed after it has been closed, and means for 15 thereafter opening said magnet operated switch.

10. An elevator wiring system embodying an elevator cage, a signal on the cage, a passenger's push button at a floor, a passenger 20 switch operable by such push button, a magnet operated switch positioned off the cage for controlling the signal, a circuit including the signal, the passenger switch and the magnet operated switch, a magnet carried 25 by the cage past and in relatively close proximity with the magnet operated switch for actuating the magnet operated switch to energize the signal after the push button has been operated, means for holding the magnet 30 operated switch closed after it has been closed, and means for thereafter opening the switch.

11. An elevator wiring system embodying an elevator cage, mounted for vertical movement in a shaft, a signal on the cage, an electric circuit for energizing said signal, a magnetically operated switch included in 45 said circuit and mounted in fixed position in the shaft, and a passenger's floor switch also 50 included in said circuit, in combination with electromagnetic means carried by the cage and at all times free from contact with the shaft switch, said electrical means being adapted, when juxtaposed with the said 55 shaft switch, to transmit energy through the intervening space to operate the stationary switch, whereby, if the passenger's floor switch is closed, the signal will be operated, means for holding the shaft switch closed 60 after it has been closed, and means, controlled by the electromagnetic means of the cage, for thereafter opening said shaft switch.

12. An elevator wiring system embodying 65 an elevator cage mounted for vertical move-

ment in a shaft, a signal in the cage, an electric circuit for energizing said signal, and means for controlling said circuit, which means embodies an electromagnet and its armature, the electromagnet being carried by the cage and its armature being mounted in relatively stationary position in the shaft and forming an electric switch, which is included in said electric circuit, means for maintaining the electric switch in 70 closed position after it has been closed, and means for thereafter opening said switch.

13. An elevator wiring system embodying an elevator cage, a signal carried by the cage, a switch operating magnet carried by the cage, an electric circuit including the signal and two stationary switches, one of which switches is adapted to be closed by an intended passenger and the other of which is positioned to be closed by the switch operating magnet as the cage moves past it in the shaft, means for maintaining at least one of said switches closed after they have been closed, and means for thereafter opening 75 said switches.

14. An elevator wiring system embodying an elevator cage, a signal in said cage, a magnetically operated switch embodying means for holding it closed after it has been closed, an electric circuit including the signal and the switch, and electromagnetic means carried by the cage in a position to be moved with the cage past and in relatively close proximity with the switch for closing the switch, in combination with additional 80 means also operable by the same electromagnetic means for subsequently opening said switch.

15. In an elevator wiring system, the combination of an elevator cage mounted to 85 travel vertically in an elevator shaft, a signal on the cage and movable therewith vertically of the shaft, a magnet carried by the cage, signal setting and restoring means for controlling the signal in the cage, said means 90 embodying switches mounted in the shaft in positions to be successively operated by the same cage magnet during its passage in proximity thereto.

16. In an elevator wiring system, the combination of an elevator cage mounted to travel vertically in an elevator shaft, an electric device, a magnet carried by the cage, energizing and de-energizing switches for controlling the operation of said electric device, said switches being mounted in the shaft in positions to be successively operated by the same cage magnet during its passage in proximity thereto, means for mechanically locking the energizing switch in closed 100 position when it is closed by the cage magnet, and means, controlled by the de-energizing switch for releasing the mechanical locking means of the energizing switch when the de-energizing switch is operated by the cage 105

magnet, said magnet being mounted on the cage in a position to be moved with the cage past and in relatively close proximity to said switches.

- 5 17. In an elevator wiring system, the combination of an elevator cage mounted to travel vertically in an elevator shaft, an electric device, a magnet carried by the cage, a push button switch, electric device setting, electric device resetting, and push button restoring means embodying switches mounted in the shaft and in positions to be successively operated by the same cage magnet during its passage in proximity thereto, 15 the electric device setting switch being included in a circuit with the electric device and the push button switch to energize the electric device when both the push button and setting switches are closed, means for 20 mechanically locking the push button, setting and restoring switches closed after they have been closed, means for unlocking said switches after they have been locked, a circuit including the restoring switch and the 25 unlocking means of the push button switch for unlocking the push button switch when the restoring switch is operated by the cage magnet, and electrical means including the resetting switch and the unlocking means of 30 the setting and restoring switches and operable when energized to unlock both the setting and restoring switches to permit them and the push button switch to assume their normal open position.
- 35 18. In an elevator wiring system, the combination of an elevator cage mounted to travel vertically in an elevator shaft, an electric device, a magnet carried by the cage, a push button switch, electric device setting, 40 electric device resetting, and push button restoring switches mounted in the shaft and in positions to be successively operated by the same cage magnet during its passage in proximity thereto, the electric device setting switch being included in a circuit with the electric device and the push button switch to energize the electric device when both the push button and setting switches are closed, means for mechanically locking 45 the push button, setting and restoring switches closed after they have been closed, means for unlocking said switches after they have been locked, a circuit including the restoring switch and the unlocking means 50 of the push button switch for unlocking the push button switch when the restoring switch is operated by the cage magnet, electrical means including the resetting switch and the unlocking means of the setting and 55 restoring switches and operable when energized to unlock both the setting and restoring switches to permit them and the push button switch to assume their normal open position, and a governor switch included in 60 the push button restoring circuit, said cage 65

magnet being mounted on the cage in a position to be moved with the cage past and in relatively close proximity to the switches in the shaft.

19. In an elevator wiring system of the character wherein the operation of a signal in a cage is controlled by a push button at a floor, an elevator cage mounted to travel in an elevator shaft, a signal in the cage, and a push button at a floor, in combination with a switch operable by the push button to be closed thereby, means for locking said push button switch in closed position after it has been closed, a restoring magnet for unlocking the push button switch to permit it to assume its normal open position, a magnet carried by the cage, a magnetically operable restoring switch mounted in the shaft and adapted to be operated by the cage magnet when the latter passes in proximity thereto, and a circuit including said restoring switch and the restoring magnet of the push button switch, whereby the push button switch is unlocked when the cage magnet passes the restoring switch. 90

20. In an elevator wiring system, the combination with an elevator cage mounted to travel vertically in an elevator shaft, of a normally inactive electric device carried by the cage, magnetically operated switch means positioned in the shaft, a circuit including said electric device and magnetically operated switch means, and a magnet carried by the cage in a position to be moved with the cage past and in relatively close proximity with the magnetically operated switch means in the shaft for the purpose of closing said electric device circuit, said switch means including means for holding said device circuit closed after operation by said cage magnet, and means for restoring said switch means to normal open position, in combination with a landing signal positioned at a floor and electrically connected to and controlled by said magnetically operated switch means. 100

21. An elevator wiring system embodying an elevator cage, an electric device carried by the cage, a normally open magnetically operable switch positioned off the cage and electrically connected with the electric device on the cage, a magnet carried by the cage and movable therewith for closing said switch to energize said device when said magnet is brought by movement of the cage into proximity with said switch, means for holding the switch in closed position after it has been closed, and means for subsequently releasing the switch to permit of opening thereof. 115

22. In an elevator wiring system, an elevator cage mounted to travel vertically in a shaft, a signal in the cage, a push button at a floor, a signal giving switch operable by said push button to be closed when the 130

push button is operated, a circuit including said switch and the signal in the cage, whereby the signal will be energized as soon as the push button is operated, means for locking said switch closed after it has been closed to maintain the signal energized, a normally open magnetically operable switch mounted in the shaft, means for unlocking the signal giving switch, a restoring circuit including 10 the unlocking means and the magnetically

operable switch to unlock the signal giving switch when the magnetically operable switch is closed, and a magnet carried by the cage and movable therewith into and out of proximity with the magnetically operable switch to close said switch to energize the restoring circuit. 15

In testimony whereof I have signed the foregoing specification.

FRANZ A. BOEDTCHER.
